UNITED STATES PATENT OFFICE.

LUELLA K. SUTTLE, OF CLEVELAND, OHIO.

DESIGN FOR THE CASING OF A TABLE-CRUMB SWEEPER.

53,184.

Specification for Design.

Patented Apr. 8, 1919.

Application filed March 30, 1918. Serial No. 225,840. Term of patent 14 years.

To all whom it may concern:

Be it known that I, LUELLA K. SUTTLE, a citizen of the United States, and resident of Cleveland, in the county of Cuyahoga and State of Ohio, have invented a certain new, original, and ornamental Design for the Casing of a Table-Crumb Sweeper, of which the following is a specification, reference being had to the accompanying drawings, forming part thereof.

In these drawings, Figure 1, is a bottom view of the casing. Fig. 2 is an end elevation; Fig. 3 is a perspective of case and cover.

I claim:

The ornamental design for the casing of a table crumb sweeper as shown.

In testimony whereof I hereunto set my hand this Mch 23, 1918.

LUELLA K. SUTTLE.

In presence of—

Wm. M. MONROE,
JOSEPH DEMBE.
